CLAIM

The ornamental design for a hair rinsing hood, as shown and described.

DESCRIPTION

FIG. 1 is a bottom perspective view of the hair rinsing hood showing my new design, the cord being shown broken to the hose element being shown partially broken away for ease of illustration;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof; and,

FIG. 6 is a bottom plan view thereof.

FIG.1.

FIG. 2.

FIG. 3.
